(57) CLAIM

We claim the ornamental design for a tongue cleaning device, as shown and described.

DESCRIPTION

FIG. 1 is a front isometric view of our new design;
FIG. 2 is a front elevation view thereof, the rear elevation
being a mirror image thereof;
FIG. 3 is a right side elevation view thereof, the left side
being a mirror image thereof;
FIG. 4 is a top plan view thereof; and,
FIG. 5 is a bottom plan view thereof.
